UNITED STATES PATENT OFFICE.

HARRY E. HEATH, OF LYNN, MASSACHUSETTS, ASSIGNOR TO GENERAL ELECTRIC COMPANY, A CORPORATION OF NEW YORK.

RESISTANCE UNIT.

No. 853,784.

Specification of Letters Patent. Patented May 14, 1907.

Application filed September 22, 1906. Serial No. 335,696.

To all whom it may concern:

Be it known that I, HARRY E. HEATH, a citizen of the United States, residing at Lynn, county of Essex, State of Massachusetts, have invented certain new and useful Improvements in Resistance Units, of which the following is a specification.

This invention relates to resistance units for electric circuits and has for its object the provision of a device of this character which can be made at a very low cost, is adapted to a variety of uses, and is at the same time thoroughly efficient, safe and durable.

In carrying out my invention I provide a sheet of insulating material, having secured thereto a resistance conductor. Resistance units have heretofore been made of a sheet of insulating material having resistance conductors secured to the surface of or within the sheet, but they have been open to objection that they are either expensive to manufacture or are limited as to the size of resistance wire to be used. For instance, it has been suggested that the resistance wire be sewed into the resistance sheet. For very small sizes of wire this might be satisfactory but it is impracticable to use the larger sizes of wire in this way. I overcome this objection by securing the resistance conductor to the sheet by means of loops which are projected through the sheet and fastened by some means, as for instance, by bending the loops back onto the sheet.

In the accompanying drawings, in which I have shown one embodiment of my invention, Figure 1 represents a plan view of my device; Fig. 2 is an end view; and Fig. 3 is a rear view of the same.

Referring to the drawings, 10 is a sheet or block of insulating material, the particular nature of which is not essential to my invention. The sheet may be flexible and composed of asbestos, fiber or the like, or it may be a stiffer and more rigid material, such as porcelain or the like. The material will depend to a certain extent upon the particular use to which the device is to be put, upon the size and the fineness of the resistance wire to be mounted thereon. A resistance conductor 11 is secured to this sheet at intervals by

means of loops 12 which are projected through the holes 13. The particular method of performing this operation is no part of my invention. The sheet may be previously perforated, and the loops forced through or in a case of flexible and easily worked material, the loops may be forced through the material by means of a punch or other appropriate implement. These loops are secured in place in any desired manner, as by bending them back onto the sheet as shown at 12. Any desired arrangement of the conductor on the sheet may be made and many other changes will suggest themselves to those skilled in the art without departing from the spirit of my invention, scope of which is set forth in the claims annexed hereto.

What I claim as new and desire to secure by Letters Patent of the United States, is,—

1. A resistance unit comprising a sheet of insulating material having a resistance conductor mounted thereon and secured at intervals by projecting loops into the sheet.

2. A resistance unit comprising a sheet of insulating material and a resistance conductor mounted thereon and secured to the sheet by projecting loops therethrough at intervals.

3. A resistance unit comprising a sheet of insulating material and a resistance conductor mounted thereon and having loops projecting through the sheet, and means for securing the loops in place.

4. A resistance unit comprising a sheet of insulating material having a resistance conductor mounted thereon and secured thereto by projecting loops through the sheet and bending them back onto the same.

5. A resistance unit comprising a sheet of insulating material having a resistance conductor mounted thereon and secured thereto by projecting loops through the sheet and bending the conductor to prevent its return.

In witness whereof, I have hereunto set my hand this twentieth day of September, 1906.

HARRY E. HEATH.
